US0D1067826S

(12) **United States Design Patent** (10) Patent No.: **US D1,067,826 S**
(45) Date of Patent: ** Mar. 25, 2025

(54) **MOTORCYCLE**

(71) Applicant: **ZHEJIANG CFMOTO POWER CO., LTD**, Hangzhou (CN)

(72) Inventors: **Chengyao Liang**, Hangzhou (CN);
Yanwei Lai, Hangzhou (CN);
Yongzhang Liu, Hangzhou (CN);
Weikang Mao, Hangzhou (CN)

(73) Assignee: **ZHEJIANG CFMOTO POWER CO., LTD**, Hangzhou (CN)

(**) Term: **15 Years**

(21) Appl. No.: **29/873,087**

(22) Filed: **Mar. 24, 2023**

(30) **Foreign Application Priority Data**

Sep. 27, 2022 (CN) 202230639217.2

(51) **LOC (15) Cl.** **12-11**

(57) **CLAIM**

The ornamental design for a motorcycle, as shown and described.

DESCRIPTION

FIG. 1 is a front and left side perspective view of a motorcycle embodying our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the motorcycle shown in faded color lines and outlined with a long-dashed, short-dashed line pattern form no part of the claimed design.

1 Claim, 7 Drawing Sheets
